UNITED STATES PATENT OFFICE.

EMERY L. WALKER, OF MILWAUKEE, WISCONSIN.

SEALING MACHINE.

1,410,279.

Specification of Letters Patent. Patented Mar. 21, 1922.

Application filed July 16, 1919. Serial No. 311,171.

To all whom it may concern:

Be it known that I, EMERY L. WALKER, a citizen of the United States, residing at Milwaukee, in the county of Milwaukee and State of Wisconsin, have invented a certain new and useful Improvement in Sealing Machines, of which the following is a full, clear, concise, and exact description, reference being had to the accompanying drawings, 10 forming a part of this specification.

My invention relates to sealing machines and more particularly to machines of this character which are used for sealing the ends of collapsible or knock-down shipping containers, which shipping containers, as distinguished from cartons are manufactured of material such as fiber board, box board or corrugated board, and are shipped in collapsed condition to the user, who fills the 20 containers with materials which are to be transported. The collapsible containers prior to their filling must have the unfolded box flaps at one extremity thereof sealed whereupon the articles to be shipped are placed in the container and thereupon the box flaps at the opposite extremity must be sealed, whereupon the shipping container with its contents is ready for shipment.

In reissue patent to Morton Serial No. 30 14,267 dated March 6, 1917, a machine is set forth which is capable of use for sealing the bottoms of the shipping containers; in my co-pending application, Serial No. 311,170, filed July 16, 1919, I set forth a machine 35 which is utilized for sealing the tops of shipping containers after the contents have been placed therein.

My present invention concerns itself with the provision of a machine so arranged as to 40 be convertible whereby it may be used for sealing the bottoms of the containers and then sealing the tops of the filled containers. My invention concerns itself particularly with the provision of a machine of this 45 character which is enabled to effect the operations outlined in connection with shipping containers of the class specified, using the heavier grades of material such as card board, box board, corrugated board or the 50 like. The use of such material presents peculiar difficulties due to irregularities and dissimilarities of the various containers which are supposed to be the same size.

My present invention concerns itself with the provision of a machine of this character 55 which accommodates itself to the irregularities and which carries out the operations outlined in a manner to satisfactorily seal the ends of boxes or shipping containers. In order to present a package satisfactory to 60 the transportation companies, it is essential that the folded box flaps be forced tightly together at their meeting edges during the sealing operation thus to present a smooth topped practically closed receptacle. 65

I will explain one form which my invention may take more in detail by referring to the accompanying drawings, in which:

Fig. 1 is a front view of one unit of a sealing machine bank constructed in accordance 70 with my invention;

Fig. 2 is a sectional view on line 2—2 of Fig. 1;

Fig. 3 is a front view of a two unit machine modified and converted into a top sealing machine; 75

Fig. 4 is a top view of the machine, certain portions being broken away to more clearly reveal features of construction;

Fig. 5 is a sectional view on line 5—5 of 80 Fig. 3;

Fig. 6 is a sectional view on line 6—6 of Fig. 5;

Fig. 7 is a sectional view on line 7—7 of 85 Fig. 5;

Fig. 8 is a sectional view on line 8—8 of Fig. 5; and

Fig. 9 is a sectional view on line 9—9 of Fig. 8.

In the drawings I have shown in Figs. 1 90 and 2 my improved machine as arranged for bottom sealing and in Figs. 3, 4 and 5, I have shown the machine converted so that it may be used for top sealing.

It must be understood that a completed 95 sealing machine is usually made up of more than one unit and the preferred form contemplates associating together a sufficient number of units so that an operator may place a shipping container for sealing into the first unit, then pass on to the next unit and to the next, so that by the time he has filled every one of the available units he can come back to unit No. 1, and find the sealing 100 operation completed. 105

Referring more particularly to Figs. 1 and

2, my improved machine consists of suitable standards 10 provided with feet 11, which may or may not be bolted to the floor, as occasion requires. Suitable cross rods 12 and 13 extend across the top of the machine and are united to the standards 10 by the double sockets 14, suitable set screws holding the rods in position in the socket structures. In accordance with my invention, I provide a supporting plate 15 which pivotally carries a socket 16, this socket having a toe 17 which limits the forward tilting movement of the socket 16 as indicated by dotted lines in Fig. 2. The socket also has a rearwardly extending arm 18 provided with an adjusting screw 19 so as to align the socket properly for purposes that will be readily apparent. The socket carries a stem 20 on top of which a platen 21 is secured. The stem 20 also carries arms 22 which hold the lower unfolded extremities of a shipping container 23. The machine as shown in Figs. 1 and 2 is designed to seal the bottoms of shipping containers as already explained. In order to effect this operation there is an upper platen 24 which cooperates with the platen 21. The upper platen 24 is movable so as to clamp the folded box ends between the platens 21 and 24 whenever the platen 24 is moved into sealing position. The platen or plunger 24 is so mounted that it may be moved up or down in response to the actuations of a handle 25, which handle controls a cam 26, the handle and cam being pivotally mounted upon a supporting framework 27 rigidly secured to the cross pieces 12 and 13 of the machine. The upper platen 24 is universally and resiliently mounted upon a stem 28 as will be more readily apparent from an inspection of Figs. 5 and 7. A pin 29 prevents the plunger 24 from sliding off from the stem 28 under the impulse of the spring 29^a which furnishes a resilient backing for the plunger 24. The cam 26 engages an adjustable structure 30 having the relatively adjustable parts 31 and 32 whereby to control the neutral position of the platen 24, this structure 30 being rigidly secured to the top of the stem 28. A spring 33 normally tends to move the stem 28 upwardly to keep the elements 32 against the surface of the cam 26. The plunger 24 likewise has downwardly extending lugs 34 at the rear thereof, which are one form of suitable stops that may be provided and against which the container may be pressed by the operator during the time that the platen 24 is moved downwardly so as to insure meeting of the abutting box flaps 35 and 36, this being of use both in the bottom and top sealing operation. The operation of the machine will be readily apparent in that the stem 20 is swung outwardly into the dotted position shown in Fig. 2, whereupon the lower unfolded extremity of the box rests

upon the arms 22 so that the scored edges of the upper flaps are aligned with the edges of the platen 21. The operator then presses the flaps into their closing position and applies the adhesive, whereupon he swings the stem 20 with the container having the bottom flaps folded, into sealing position, that is the position shown in full lines in Fig. 2. Thereupon the operator moves the handle 25 counterclockwise thus forcing the plunger 24 downwardly into sealing position and locking it in that position. The machine as thus far described is useful for what is called bottom sealing of the containers.

Now in order to arrange the machine for the top sealing of the filled containers, I provide additional instrumentalities. In the first place, it is necessary to remove the stem 20 with the platen 21 and to do this the set screw 37 is released thus leaving the socket 16 empty. This is shown more clearly in Figs. 3 and 5. At the same time an alternative lower platen 38 is mounted in position upon the standards 10 at the proper height so that it may receive the filled container 40. A downward actuation of the plunger 24 after the container 40 is in position of Fig. 5, will if the folded ends have been properly supplied with adhesive effect the sealing of the top of the container. In order to adjust the platen 38 into proper position, I provide a collar 41 having teeth 42 which cooperate with pins 43, which pins are placed as required in holes 44 at the proper height. Suitable supports 45 are then mounted on top of the collars 41 and the platen 38 as will be noted is removably mounted so that when it is taken away the stem 20 can again be inserted in place in the socket 16. In order to properly align the platens 38 they are provided with rounded cut-away portions 46 which snugly fit the standards 10. The supports 45 have forwardly extending arms 47 which serve as a worktable and which may desirably support the plate 48 for that purpose. The platens 38 are also provided with rollers 49 which assist in transferring the filled shipping container from the plate 48 to the platen 38. In operating the device for sealing the tops of the shipping containers the operator places the filled containers on top of the plate 48, folds two of the box flaps inwardly, applies the adhesive and then pushes the filled container with its flaps folded inwardly into the position shown in Fig. 5. The platen 24 is then moved downwardly at the same time that the operator pushes the upper part of the container against the stops 34.

In my copending application above referred to I have claimed broadly a machine of use for top sealing of shipping containers, also the means for adjusting the platen and also the roller structure 49 and the stop

structure 34; reserving for this application the claims directed to the convertible feature of the machine herein described.

In my copending application Serial No. 5 311,173 filed July 16, 1919, I illustrate and claim a machine, in which both lower platens which are interchangeably used are pivotally mounted. The claims directed to that 10 feature are made in that particular application.

While I have herein shown and particularly described one form which my invention may take it will be, of course, apparent that many modifications can be made

15 within the scope of the appending claims without departing from the spirit of my invention. I claim the following:—

1. A sealing machine of the character described adapted for alternatively sealing the 20 bottom and top flaps of shipping containers comprising a framework, an upper platen mounted on said frame work, a lower bottom sealing platen and means on said framework for supporting a top sealing platen 25 below said bottom sealing platen.

2. A sealing machine of the character described adapted for alternatively sealing the bottom and top flaps of shipping containers comprising a framework, an upper platen 30 mounted on said framework, a lower adjustable bottom sealing platen and means on said framework for adjustably supporting a top sealing platen below said bottom sealing platen.

3. A sealing machine of the character described adapted for alternatively sealing the bottom and top flaps of shipping containers comprising a framework, an upper platen mounted on said framework, means along 40 one edge of said upper platen against which opposing container end flaps may be pressed prior to sealing, a lower bottom sealing platen and means on said framework for supporting a top sealing platen below said bottom sealing platen.

4. A sealing machine of the character described adapted for alternatively sealing the bottom and top flaps of shipping containers comprising a framework, an upper platen 50 mounted on said framework, means along one edge of said upper platen against which opposing container end flaps may be pressed prior to sealing, a lower adjustable bottom sealing platen and means on said framework for adjustably supporting a top sealing platen below said bottom sealing platen.

5. A sealing machine of the character described adapted for alternatively sealing the bottom and top flaps of shipping containers 60 comprising a framework, an upper platen universally and yieldingly mounted on said framework, means for movably supporting a bottom sealing platen close to said upper platen, and means on said framework for

stationarily supporting a top sealing platen 65 properly spaced from said upper platen.

6. A sealing machine of the character described adapted for alternatively sealing the bottom and top flaps of shipping containers comprising a framework, an upper platen 70 mounted on said framework, means along one edge of said platen against which opposing end flaps may be pressed prior to sealing, means for movably supporting a bottom sealing platen close to said upper platen, and 75 means on said framework for stationarily supporting a top sealing platen properly spaced from said upper platen.

7. A sealing machine of the character described adapted for alternatively sealing the 80 bottom and top flaps of shipping containers comprising a framework, an upper platen mounted on said framework, means for movably and adjustably supporting a bottom sealing platen close to said upper platen, 85 and means on said framework for stationarily and adjustably supporting a top sealing platen properly spaced from said upper platen.

8. A sealing machine of the character described adapted for alternatively sealing the bottom and top flaps of shipping containers comprising a framework, an upper platen 90 mounted on said framework, centrally located means for swingingly and removably 95 supporting a bottom sealing platen close to said upper platen, and means on said framework for stationarily and removably supporting a top sealing platen properly spaced from said upper platen, the supporting 100 means of either of said latter platens being so located as to be out of the path of operation of the other of said platens when in operative position.

9. A sealing machine of the character described adapted for alternatively sealing the top and bottom flap of shipping containers comprising a framework having a pair of fixed standards, an upper platen mounted on said framework, a lower bottom sealing 105 platen, and sleeves adjustably mounted on said framework for adjustably supporting a top sealing platen below said bottom sealing platen.

10. A sealing machine of the character described adapted for alternatively sealing the top and bottom flap of shipping containers comprising a framework having a pair of fixed standards, an upper platen mounted on 110 said framework, a lower bottom sealing platen, and sleeves adjustably mounted on said framework for adjustably supporting a top sealing platen below said bottom sealing platen, said sleeves being mounted so as to be capable of both a rough and fine adjustment. 115 120 125

11. A sealing machine of the character described adapted for alternatively sealing the top and bottom flap of shipping containers

comprising a framework having a pair of fixed standards, an upper platen mounted on said framework, a lower bottom sealing platen, and sleeves adjustably mounted on said framework for adjustably supporting a top sealing platen below said bottom sealing platen, said sleeves being mounted so as to be

capable of both a rough and fine adjustment and being provided with arms for removably supporting said top sealing platen. 10

In witness whereof, I hereunto subscribe my name this 2nd day of July, A. D., 1919.

EMERY L. WALKER.
